RETARDING FIELD OSCILLATORS

Bernard C. Gardner, Los Altos, Calif., assignor to Raytheon Manufacturing Company, Newton, Mass., a corporation of Delaware

Application April 8, 1952, Serial No. 281,091

5 Claims. (Cl. 313—85)

This invention relates to retarding field oscillators and, more particularly, to the repeller electrode structure in such oscillators.

By retarding field oscillators is meant oscillators of the type described by Heil and Ebers in an article entitled "A new wide range high-frequency oscillator," in the June 1950 issue of the Proceedings of the IRE, at pages 645-650. Oscillators of this type are clearly distinguished from velocity-modulated oscillators of the reflex type utilizing the tubes commonly known as reflex klystrons in a second article by Ebers entitled "Retarding field oscillators" in the February 1952 issue of the same publication, beginning on page 138 and especially at page 141. Briefly, in the reflex klystron the electrons are velocity-modulated in the concentric radio-frequency field between the anode and the grid. They then drift and bunch in the repeller region and return to do work in the radio-frequency field. In the Heil type of tube, the electrons are velocity-modulated by the concentrated radio-frequency field near the nozzle-shaped anode. They then drift and bunch in a relatively weak radio-frequency field and return to do work on the strong radio-frequency field. In this process, the electron beam is expanded or contracted in the nozzle area or just beyond depending on the phase of the oscillation. The return beam will have periodic density variations which tend to modulate the outward-going beam in such a way as to deliver energy to the oscillating circuit.

The repeller electrode in such an oscillator is a tube which, for wide-band operation, will, in cooperation with the anode, produce a more or less uniform field. The beam of electrons will be projected up into the repeller tube, more or less depending upon the phase of the oscillation, but since the field is uniform over narrow ranges of penetration there will be a rather uniform focusing condition throughout the cycle.

The invention consists in modifying the repeller structure of such an oscillator so that either a spike of conductive material protrudes from a transverse plane of conductive material within the repeller tube in the direction of the oncoming electron beam, or there are openings formed in the end of the repeller tube nearest the anode. With either repeller construction, a very non-uniform focusing field is obtained within the repeller tube. The electrons entering this field, in a phase which causes them to penetrate further in, will tend to be defocused on the back trip more than those entering in the opposite phase. Consequently, the modulation will be greater and there will be more activity permitting greater efficiency in operation. The structure can be modified to operate efficiently over a wide range of frequency by arranging the spike so that it is not moved as the tube is moved. The same effect can be obtained by applying a voltage to the spike that can be varied independently of the voltage applied to the repeller tube. With this arrangement, the voltage may be adjusted to an optimum value for the particular wave length to which the oscillator is adjusted.

2

The foregoing and other advantages, objects, and features of the invention will be better understood from the following description taken in conjunction with the accompanying drawings wherein:

Fig. 1 is a longitudinal cross section of one embodiment of the invention;

Fig. 2 is a schematic diagram of the circuit associated with the embodiment of Fig. 1;

Fig. 3 is an enlarged view of a part of the embodiment shown in Fig. 1;

Fig. 4 is a modification of the structure shown in Fig. 3; and

Fig. 5 is a section taken along a line 5—5 of Fig. 4.

In Fig. 1, the reference numeral 10 refers to the envelope of a retarded field oscillator tube of the type described above. Within this envelope is mounted a hollow spheroid cathode 11 heated by a coil 12. Electrons emitted from the cathode 11 are accelerated toward and through an annular conical opening 13 in the wall of the resonant cavity resonator 14 which concentrates the electrons into a narrow beam and projects them into a hollow cylindrical repeller electrode designated generally by the reference numeral 15.

The construction of this electrode can best be seen in Fig. 3. It is constructed of a tube 16 of insulating material with a coating 17 of conductive material on the outside that extends into the interior. The tube 16 is mounted so as to be electrically isolated for direct current from the wall of the opening 18 in the cavity resonator 14 but coupled capacitively to the cavity resonator at radio frequency through a virtual short circuit. The repeller tube 16 is arranged to be moved with respect to the opening 13 for tuning purposes. This is accomplished by attaching a rod 20 to the end of the tube 16, and passing it through the envelope 10 by means of a bellows 21, that permits the rod 20 to be moved in either of the directions indicated by the arrows 22 and 23 while retaining the vacuum within the envelope 10. If it is desired to maintain the rod 24 at a potential different from that of the surface 17 of the tube 16, the rod is mounted in a manner to insulate it from the tube 16. The rod 24 is formed with a spike 25 at the end nearest the opening 13. With the mounting shown in Fig. 1, the rod 24 remains in position while the tube 16 is moved. A terminal 26 is formed on the end of the rod 24 to connect it to a source of potential.

The potentials applied to the various electrodes can best be seen from the schematic diagram of Fig. 2. A source 27 of negative potential is connected between the cathode 11 and the cavity resonator 14, the positive terminal of a second source 28 of potential is connected to the cavity resonator 14 and a tap 29 is connected to the repeller tube 16. The rod 24 is connected to a second tap 30 on the source of negative potential 28. This is an optional connection to enable the repeller tube 16 and the rod 24 to be maintained at different potentials that can be independently adjusted. If this is not desired, the rod 24 and tube 16 may be connected together to the source 28.

The effect of the spike 25 upon the operation of the oscillator is best understood by reference to Fig. 3. It will be seen that the beam of electrons 31 is emitted from the cathode 11 and concentrated by the anode 13. The electrostatic field between the repeller 15 and the anode 13 is represented by the equipotential lines 32, shown dotted. It will be seen that the electron stream 31 splits as it approaches the spike 25 and returns to the outside of the anode 13. The dotted lines 32 show that the electrostatic field in this region is not uniform. As a result, the electrons entering this field, in a phase which causes them to penetrate further in, will tend to be de-

focused on the back trip more than those entering in the opposite phase. This modulation will be greater than that which would be produced if the spike were not present. This greater modulation results in more activity and in more efficient operation.

The range over which the oscillator can be operated with reasonable efficiency can be extended by maintaining the rod 24 stationary as the distance of the repeller tube 16 from the anode 13 is varied to vary the capacity between the elements, thus varying the resonant frequency of the cavity resonator 14.

The same objective can be achieved by establishing a potential on the rod 24 that is independent of the potential on the surface 17 of the tube 16. This independent potential can then be adjusted to give the best result at each operating frequency over a wide range.

Figs. 4 and 5 show how these effects may be obtained by another construction of the repeller electrode. The repeller tube 33 is formed with a main section 34, and a second short concentric section 35 of the same diameter connected to the main section by a plurality of rods 36 arranged with their axes parallel to that of the repeller tube 33 and in the cylindrical surface of the tube. The effect of the openings between the rods 36 is to distort the focused field in much the same manner as the arrangement shown in Fig. 3. The resulting field is shown by the equipotential lines 37, shown dotted. The same effect can be obtained by slots cut into the walls of the repeller tube 33.

This invention is not limited to the particular details of construction, materials and processes described, as many equivalents will suggest themselves to those skilled in the art.

What is claimed is:

1. A retarding field oscillator comprising a cathode formed with a hemispherical concave surface, a conical annular accelerating electrode having tapered inner edges forming a focussing electrical field in this region, and a repeller electrode disposed along a common axis, said repeller electrode comprising a hollow cylindrical member, and means near the end of the repeller nearest the accelerating electrode to distort the focusing field.

2. A retarding field oscillator comprising a cathode, a conical annular accelerating electrode having tapered inner edges forming a focussing electrical field in this region, and a repeller electrode disposed along a common axis, said repeller electrode comprising a hollow cylindrical member, and means near the end of repeller nearest the accelerating electrode to distort the focusing field, said means comprising openings in the walls of the repeller electrode.

3. A retarding field oscillator comprising a cathode

formed with a hemispherical concave surface, a conical annular accelerating electrode having tapered inner edges forming a focussing electrical field in this region, and a repeller electrode disposed along a common axis, said repeller electrode comprising a hollow cylindrical member, and means near the end of the repeller nearest the accelerating electrode to distort the focusing field, said means comprising conductive material disposed within the repeller electrode in a plane transverse to the electron stream and a conductive rod projecting from the said plane toward the accelerating electrode parallel to the electron stream.

4. A retarding field oscillator comprising a cathode formed with a hemispherical concave surface, a conical annular accelerating electrode having tapered inner edges forming a focussing electrical field in this region, and a repeller electrode disposed along a common axis, said repeller electrode comprising a hollow cylindrical member, and means near the end of the repeller nearest the accelerating electrode to distort the focusing field, said means comprising conductive material disposed within the repeller electrode in a plane transverse to the electron stream and a conductive rod projecting from the said plane toward the accelerating electrode parallel to the electron stream, and means to cause relative motion between said rod and said cylindrical repeller electrode.

5. A retarding field oscillator comprising a cathode formed with a hemispherical concave surface, a conical annular accelerating electrode having tapered inner edges forming a focussing electrical field in this region, and a repeller electrode disposed along a common axis, said repeller electrode comprising a hollow cylindrical member, and means near the end of the repeller nearest the accelerating electrode to distort the focusing field, said means comprising conductive material disposed within the repeller electrode in a plane transverse to the electron stream and a conductive rod projecting from the said plane toward the accelerating electrode parallel to the electron stream, and means to maintain the repeller electrode and the rod at separate potentials negative with respect to that of the accelerating electrode.
